(57) **CLAIM**

The ornamental design for automobile alarm clock radio, as shown and described.

DESCRIPTION

FIG. 1 is a perspective view of an automobile alarm clock radio of the present invention having a time information display in the windshield thereof and a radio information display in a side window thereof;

FIG. 2 is a perspective view of the automobile alarm clock radio of FIG. 1 having a radio information display in the windshield and a time information display in the side window;

FIG. 3 is a front perspective view of an automobile alarm clock radio according to the present invention having a time information display in the windshield;

FIG. 4 is a front perspective view of the automobile alarm clock radio according to the present invention having a radio information display in the windshield;

FIG. 5 is a rear perspective view of the automobile alarm clock radio according to the present invention; and,

FIG. 6 is a rear perspective view of another embodiment of the automobile alarm clock radio according to FIG. 5.

The broken lines depicting an automobile body, wheels and informational displays are for illustrative purposes only and form no part of the design.
